UNITED STATES PATENT OFFICE.

ANDREW A. WALSH, OF BAYONNE, NEW JERSEY, ASSIGNOR OF ONE-HALF TO WILLIAM J. COUGHLIN, OF BAYONNE, NEW JERSEY.

COMBINATION PLUMBING FIXTURE.

Application filed December 21, 1923. Serial No. 682,012.

To all whom it may concern:

Be it known that I, ANDREW A. WALSH, a citizen of the United States, and resident of Bayonne, in the county of Hudson and 5 State of New Jersey, have invented certain new and useful Improvements in a Combination Plumbing Fixture, of which the following is a specification.

The object of this invention is the production of a combination plumbing fixture, the 10 essential portions of which are integral or cast together.

The object of the invention is the production of a combination fixture which can be 15 easily installed in place and is of low first cost.

It is provided with a detachable extension platform and extension walls to form a housing suitable for a shower bath. The extension platform and extension walls can be 20 easily connected to the main portion of the fixture. The detachable feature of the extension platform and walls allows the fixture to pass through the ordinary door openings of a building to install it in place.

In the accompanying drawings which 25 represent one exemplification of the invention, Fig. 1 shows a front elevation of the combination plumbing fixture with a modification in dotted lines; Fig. 2 indicates a partial section of Fig. 1 on the line 2, 2; Fig. 2^a shows a fragmentary portion of Fig. 2 on a reduced scale with a modification; Fig. 3 is a top plan view of Fig. 1; Fig. 3^a 35 shows a fragmentary portion of Fig. 3 on a reduced scale with the modification; Fig. 4 represents a section of Fig. 3 on the line 4, 4 and Fig. 5 indicates a section of Fig. 3 on the broken line 5, 5.

An inclined main platform 20 inclines toward 40 its rear end and has extending up therefrom the side walls 21, each with a groove 22 in its upper end. Side gutters 23 formed in the platform adjacent to its side walls 21 incline toward the rear portion thereof, and join with the rear gutter 24 formed in the platform. An inclined shower outlet and slop sink 25 in the rear portion of the platform joins with the said rear gutter.

Side extension walls 26 each with the 45 groove 27 in its upper edge extend from the side walls 21. A rear extension wall 28 connects the walls 26 and has formed in its upper edge the groove 29, which connects with

the grooves 27. A front wall 30 with the tapered upper portion 31 and the central foot 32 extends from the lower face of the front portion of the platform 20. Openings 33, similar to 68 to be described, are preferably formed in the wall 30. Feet 35 are formed at the ends of the wall 30 and similar feet 36 are formed at the junction of the rear wall and the side walls of the said platform.

A water closet 40 with the flushing ring 41 and the trap 42 having the outlet end 43, is cast integral with the platform 20 and the wall 28.

A soil and vent pipe 45 with the clean out 46 is connected at its lower end to the outlet end 43 and the upper end of said pipe is connected to the wall 28.

A plug 47 for an opening in the soil and vent pipe 45 is provided for another connection not shown. Flush piping 48 is connected to the water closet 40 in the usual way.

A trap 55 connects the inclined shower outlet and slop sink 25 with the soil and vent pipe 45. A strainer head 56 is secured in a depressed portion of the roof of said inclined shower outlet and slop sink 25, and its openings lead to the trap 55.

An inclined extension platform 60 having the front wall 61, inclines toward its rear portion, and registers with the front portion of the platform 20.

The platform 60 has extending up therefrom the side wall 62 which register with the side walls 21. Grooves 63 in the walls 62 register with the grooves 22. Side gutters 64 are formed in the platform 60 adjacent to its side walls 62. The gutters 64 incline toward the rear portion of the platform 60 and register with the gutters 23. A rear wall 65 with the tapered upper portion 66, and the central foot 67 extends from the lower face of the rear portion of the platform 60. Openings 68 are preferably formed in the wall 65. The walls 30 and 65 are connected by the bolts 69 and cement 70 secures a water tight joint between the platforms 20 and 60. Feet 73 are formed at the ends of the wall 65 and similar feet 74 are formed at the front and sides of said platform 60.

A wash basin 75 is cast integral with the rear wall 28. The opening in its lower portion is provided with the outlet pipe 79 that

extends to the gutter 24. A pair of faucets 82 for the wash basin 75 have connected thereto piping 83 in the usual way.

Referring to the modification indicated in Figs. 2^a and 3^a, the vent pipe is again shown at 45, the wash basin at 75, the faucets at 82 with the piping 83. A trap for the outlet of the wash basin 75 is shown at 80 with its piping 81, in place of the pipe 79. The piping 81 connects with the vent pipe 45.

Detachable side extension walls 86 with the offset portion 87 have respectively formed at their lower edges the tenons 88-89, 15 that are engaged by the grooves 63 and 27. A rear detachable extension wall 90 has formed therewith the tenon 91 which is engaged by the groove 29. The walls 86 and 90 may be connected by knee-brackets 94 and 20 form with the walls 25 a housing for the fixture.

A spray head 95 extends from the piping 96 and provides a shower bath for the fixture.

25 Various modifications may be made in the invention and the present exemplification is to be taken as illustrative and not limitative thereof.

Having described my invention what I desire to secure by Letters Patent and claim is:—

30 1. In a combination plumbing fixture the combination of a platform, a closet integral with and extending up from the platform, 35 a trap integral with the closet, a soil pipe for the closet and integral with the outlet end of said trap, a slop sink formed with said platform and a trap connecting said slop sink and the soil pipe and integral therewith.

2. In a combination plumbing fixture the combination of a main platform, a front extension platform detachably connected to the main platform, a closet integral with the main platform, a trap integral with the closet, a soil pipe for the closet integral with the outlet end of said trap, a slop sink formed with the main platform and a trap connecting the slop sink and said soil pipe and integral therewith.

3. In a combination plumbing fixture the combination of a main platform, a front extension platform detachably connected to the main platform, detachable extension walls for the fixture, a closet, a slop sink and a soil pipe formed integral with the main platform.

4. A combination plumbing fixture comprising a main platform inclined toward its

rear end, gutters formed at the sides of the 60 platform, a gutter formed at the rear of the platform connecting with the gutters at the sides thereof, an inclined shower outlet and slop sink formed in the platform extending to its rear gutter, a water closet 65 integral with said platform, a soil and vent pipe integral with the platform, a trap integral with the soil and vent pipe and said water closet and a trap integral with the 70 said shower outlet and slop sink and said soil and vent pipe.

5. A combination plumbing fixture comprising a main platform inclined toward its rear end, an inclined shower outlet and slop sink formed with the platform, a water 75 closet integral with said platform, a soil and vent pipe integral with the platform and said water closet, a trap integral with said shower outlet and slop sink and said soil and vent pipe, a housing for the platform 80 and a spray head for a shower bath for the fixture, the water discharged from the spray head escaping through said shower outlet and slop sink.

6. A combination plumbing fixture comprising a main platform, a gutter at the rear portion of the platform, a water closet integral with said platform, a soil and vent pipe integral with said platform and said water closet, a shower outlet and slop sink 90 integral with said platform, a rear wall extending from the platform, a wash basin integral with the said rear wall and piping extending from said wash basin to said gutter.

7. A combination plumbing fixture comprising a main platform, side extension walls for the platform, a rear extension wall for the platform connected to said side extension walls, an inclined shower outlet and 100 slop sink formed with said platform, a soil and vent pipe formed with the platform, a trap integral with said pipe and said shower outlet and slop sink, an extension platform connected to the main platform, detachable 105 side extension walls for the platforms, a rear detachable extension wall connected to the detachable side extension walls and to the rear extension wall, and a spray head for a shower bath above said platforms, the water 110 discharged from the spray head escaping through said shower outlet and slop sink.

Signed at the borough of Manhattan, city of New York, in the county of New York and State of New York, this 7th day of December A. D. 1923.

ANDREW A. WALSH.
